Aktiebolaget Electrolux, Stockholm, Sweden, a corpora-
tion of Sweden

Filed Nov. 25, 1964, Ser. No. 82,800

Claims priority, application Sweden May 29, 1964

Term of patent 14 years

(Cl. D9—2)

FIG. 1

FIG. 3

FIG. 2

FIG. 4

FIG. 5

FIG. 6

FIG. 7

FIG. 8

FIGURE 1 is a front perspective view of a suction cleaner casing showing the top and one side of my new design;

FIGURE 2 is a rear perspective view showing the top and opposite side thereof;

FIGURE 3 is a bottom perspective view thereof;

FIGURES 4 and 5 are respectively top and bottom plan views thereof;

FIGURE 6 is a side elevational view thereof; and

FIGURES 7 and 8 are respectively front and rear elevational views thereof.

I claim:

The ornamental design for a suction cleaner casing, as shown.
